Patented May 13, 1919.

UNITED STATES PATENT OFFICE.

CHARLES B. ANDREWS, OF HIGH BRIDGE, NEW JERSEY, ASSIGNOR TO TAYLOR WHARTON IRON AND STEEL COMPANY, OF HIGH BRIDGE, NEW JERSEY, A CORPORATION OF NEW JERSEY.

GYRATORY CRUSHER-HEAD.

1,303,447.

Specification of Letters Patent.

Patented May 13, 1919.

Application filed January 23, 1918. Serial No. 213,286.

To all whom it may concern:

Be it known that I, CHARLES B. ANDREWS, United States citizen, residing in High Bridge, New Jersey, have invented the following described Improvements in Gyratory Crusher-Heads.

The improvement concerns the mounting of the mantles on the cores and also of the cores on the shafts of rotary or gyratory crushing mills, the object being to secure and maintain the mantle in a rigid relation to the shaft notwithstanding its wear and distortion or stretching under the strains of use. To this end the invention consists in providing separate take-ups for core and mantle and a special means of locking the one to the other which is unaffected by their relative positions and also in means for automatically taking up looseness of the mantle as and when it develops in use, all of these features serving independently and collectively to minimize the cost of maintenance and increase the efficiency of mills of this class as will hereafter be made apparent.

25 In the accompanying drawings:

Figure 1 is an elevation of a crusher head partly in section and partly broken away;

Fig. 2 an end view of the same;

Fig. 3 a radial section at the key; and

30 Fig. 4 a perspective of a suitable form of key.

The shaft 1 is slightly coned to receive the core 2 which is keyed or fitted non-rotatively thereon in any approved manner and pressed 35 toward the larger diameter of the shaft by a ring nut 3 threaded on the shaft and abutting against the smaller end 4 of the core. The ring nut 3 is locked to the shaft to prevent loosening in service, by a key 3^a inserted in one of several key seats 3^b provided for the purpose. The core is externally coned to receive the internally coned mantle 5, and the latter is usually and preferably made of manganese steel or any tough metal 40 specially suited to resist abrasion. In the present case it is cast with internally elevated grinding pads or surfaces 6, which are ground down to fit and form a bearing upon the external conical surface of the core, 45 the intervening spaces between pads being filled in with molten zinc or other filling, according to the practice common in the art. The mantle is held non-rotatively to the core partly by its friction thereon, for which pur-

pose a ring nut 7 is provided thrusting 55 against its smaller end 8 and adapted to press it firmly toward the larger end of the core. This ring nut is threaded to the ring nut 3, being thus adjustable independently thereof, and a key 7^a is provided to prevent 60 rotation thereon in service. Both nuts are threaded with the same direction of pitch, right-handed in the case shown in the drawings. The mantle is also secured against rotation upon the core by a special key, separately shown in Fig. 4, and which is provided with one part 9, adapted to occupy a square notch 10 formed in the small end of the core beneath the thrust face of the ring nut 3, and another part 11, adapted to occupy a notch 12 in the small end of the mantle beneath the face of ring nut 7. The part 9 of the key, seated in the core, is desirably larger than the part 11 seated in the mantle, so that the key is thereby held against accidental dislodgment although it may be otherwise secured or confined in position as desired. The notches for both parts of the key may be deeper than the corresponding key parts so that the key receives none of 80 the pressure of the nuts but is nevertheless available to lock the parts against rotation. While the key may be variously related to the other parts to perform the function stated, it is preferably arranged so that the 85 surface of engagement between it and the mantle has an inclination to the direction of any rotary motion of the latter if any should take place and so as to produce a wedging action acting on the mantle to force it into 90 tighter engagement with the core. This effect is produced by giving the key part 11 the triangular shape indicated in the drawings and correspondingly shaping the notch 12 with which it engages, which formation 95 results in forcing or wedging the mantle longitudinally of the shaft and in the direction of the larger end of the core thus tightening the mantle if loose. It is preferred to have the wedging engagement just referred 100 to occur between the mantle and the key part 11 as shown in the drawings but manifestly the wedging surfaces may be variously related to the mantle to give the same effect and so that when the mantle develops 105 a tendency to rotate on the core as the result of its enlargement or stretching under use, such rotation will be resisted not only by the

obstruction represented by the key itself but also by the wedging thrust on the mantle which restores its friction on its seat. The pressure of the mantle on the key part 11 is thus resolved into two component pressures. One of them acting on the mantle tends to tighten it. The other acting on and through the key part presses it into contact with the edge of ring nut 7 and thereby tends to lock that nut against unscrewing which fact in turn also tends to increase the locking effect upon the inner ring nut 3. Thus it will be seen that the entire head is adapted to remain tight for indefinite periods and that the ring nut will require to be tightened only at infrequent intervals. It is obvious that the function of the key and of the wedging surfaces are independent of the manner of attachment of the core to the shaft, which latter may therefore be made integral with the core in certain forms of the invention, and likewise that various additions, subtractions, substitutions, reversals and modifications may be resorted to within the invention and without sacrificing the benefits of the principles thereof which have now been explained and which are more particularly identified in the following claims.

Claims.

30 1. A crusher head mounting comprising a tapered seat, a mantle thereon, means engag-

ing the end of the mantle to force it on the seat and a key interlocking the mantle and seat and removably confined in place by said means.

35

2. In a crusher head mounting, a tapered core carrying a tapered mantle, separate screw thread rings for forcing each in an endwise direction and a removable key engaging notches in the mantle and core respectively.

3. A crusher head mounting comprising a tapered core and mantle, a separate ring nut for forcing each in an endwise direction and a removable key confined in registering notches in said core and mantle.

45

4. A crusher head comprising a crusher shaft having a tapered seat for an externally tapered core, an internally tapered mantle seated on the core and ring nuts having the same direction of pitch for separately forcing the core and mantle toward the larger ends of their respective seats.

50

5. A crusher head mounting comprising an internally tapered mantle keyed to a tapered mantle seat and a ring nut having a thrust face proximate to thrust surfaces on the mantle and key, respectively, and adapted to engage either.

55

In testimony whereof, I have signed this specification.

CHARLES B. ANDREWS.
